UNITED STATES PATENT OFFICE

THOMAS W. PROSSER, OF KANKAKEE, ILLINOIS, ASSIGNOR TO PARAMOUNT TEXTILE MACHINERY CO., OF CHICAGO, ILLINOIS, A CORPORATION OF ILLINOIS

HOSIERY DRYING FORM

Application filed June 20, 1929. Serial No. 372,344.

This invention relates to hosiery drying forms, the improvement residing particularly in the construction of the form to provide even drying of the several portions of

5 a hosiery article placed upon the form.

Two types of hosiery drying forms are known to the prior art, the so-called flat form and the oval form. Each of these has its particular advantages, but there are also 10 certain disadvantages resulting in the finished stockings due to the construction of the form. For example, stockings finished upon the flat forms have a tendency to lie flat when they are removed from the form and 15 thus they satisfy this requirement of the trade; but it is found that they do not smooth out the wrinkles which occur in the reinforced portions of the stockings. In actual practice, stockings after they are re- 20 moved from the flat forms are submitted to a pressing operation to put in the creases at the front and rear of the stocking, and at the same time the wrinkles in the reinforced portions are pressed out. The flat 25 forms referred to are those which have generally been used in connection with so-called drying boxes, and these are still in use to some extent in the trade.

With the advent of the so-called internally 30 heated form, it was quite natural to attempt to make these forms flat and as nearly like the wooden boards theretofore in use as possible. Such forms were constructed and used, and the goods after being finished 35 were submitted to the pressing operation for putting in the creases and for smoothing out the wrinkles in the reinforced portions of the stockings. In order to complete the entire operation of finishing a stocking upon 40 a form, the internally heated forms were provided with crease-producing edges, and some thickness was given to the form in order to somewhat stretch the fabric and thus insure removal of wrinkles in the reinforced 45 portions. The oval form disclosed in the patent to Butz No. 1,207,496 is typical of the type of form here referred to. This form, while inherently satisfactory in the 50 finishing of stockings, is nevertheless thought to be somewhat objectionable in that after

the stocking is removed from the form, it has a tendency to curl or cup and the fabric will not lie as flat as when finished on a flat form.

Furthermore, the types of forms herein 55 referred to have made no provision for the distribution of the heating medium so as to provide an even drying of the stockings. As is well understood, the heavier, reinforced portions of a stocking contain more 60 moisture to be evaporated and, consequently, it takes longer for these portions to dry. In the meantime, the lighter fabric of the stocking has been dried, and where the stocking is of the extremely light fabric now so 65 prevalent, it is found that the light fabric bakes on the form while the reinforced portions dry and set.

It is a primary object of my invention to provide a hosiery drying form which 70 shall embody the advantages of the types of forms heretofore devised and which does not possess the disadvantages thereof, as above pointed out.

It is another object of my invention to 75 provide a hosiery drying form of varying cross-sectional area, the greater cross-sectional area being located in that part of the form which contacts with the reinforced portions of a stocking, and the remaining parts 80 of the form being relatively flat.

A form constructed in accordance with my invention possesses the advantageous feature of the flat form, in that the fabric, after being removed from the form, tends 85 to lie flat, and I also obtain the advantage of the so-called oval forms in that wrinkles in the reinforced portions of the stocking are smoothed out while the stocking is on the form, thus eliminating the subsequent 90 pressing operation. Furthermore, by the construction of form which I have invented, a stocking is more uniformly dried, in that that part of the form which contacts with the reinforced portions of the stocking is of 95 relatively greater cross-sectional area and thus contains a greater quantity of the heating medium.

Other objects of my invention, as well as the many advantages thereof, will be more 100

fully brought out as the description of the invention proceeds.

In the accompanying drawing, I have illustrated a preferred embodiment of my invention; but it is to be understood that the drawing is illustrative merely and that the invention is not confined to the details of construction therein disclosed. Those skilled in the art will readily appreciate that 10 the invention is susceptible of other embodiments than that herein described and illustrated, and that many modifications may be made, all falling within the scope of my invention as defined in the appended 15 claims.

In the drawing:

Figure 1 is a side elevation of a hosiery drying form embodying my invention; and

Figures 2, 3, 4 and 5 are cross-sectional views taken on lines 2—2, 3—3, 4—4 and 5—5, respectively, of Fig. 1, these cross-sectional views being on an enlarged scale but maintaining substantially the same relative proportions.

25 The hosiery drawing form of my invention is composed of side members 6, 6, terminating in a front crease-producing edge 7 and a rear crease-producing edge 8. The sides of the form may be made of sheet metal suitably secured together at the edges 7 and 8; or the form may be cast of aluminum or any other material found to be practical in actual use. It is to be understood also that the edges 7 and 8 need not necessarily be 30 substantially reduced to provide crease-producing edges; it may sometimes be desirable to leave the edges slightly rounded.

Whether the form be made of sheet metal or cast of aluminum, it will be so constructed 40 that the side members 6 enclose a chamber or cavity 9 adapted to contain any suitable heating medium, such as steam or hot water, it being understood that my invention is not confined to the use of any particular type of heating medium.

The construction of my form by reason of which I accomplish the results pointed out will best be understood by referring to the sectional views disclosed in Figs. 2 to 5, 50 inclusive. Fig. 2 is a sectional view of the form, taken through the foot portion, and shows that the cross-sectional area of the form is relatively greater in that part of the form which contacts with the double sole of the hosiery article placed thereon.

The sectional view in Fig. 3 is taken at the ankle portion of the form, and shows that at this part of the form it is of relatively greater cross-sectional area where the heel reinforcement contacts with the form.

In order to provide for the uniform drying of stockings having the ornamental types of heel reinforcement now so prevalent in use, this increase in the cross-sectional area may 65 be extended a suitable distance down along

the rear crease-producing edge. The increased cross-sectional area will taper gradually from about the ankle portion to a point along the calf, as is illustrated in Fig. 4 in which the increased cross-sectional area 70 has practically vanished.

The sectional view in Fig. 5 discloses the construction of the form below the calf and it is seen that the form is here practically flat. This view, therefore, emphasizes the 75 difference in cross-sectional area of the form in those parts with which the reinforced portions of a stocking contact and the parts which contact with the lighter fabric of the stocking.

80 Thus, the side members 6 of the hosiery drying form of my invention may be said to be bulged away from each other a greater distance at or near the rear crease-producing edge and in that part of the form with 85 which the double sole of a stocking contacts, this bulging being gradually reduced from about the ankle section to a point near the calf, at which point the sides of the form are practically flat and are practically uniformly spaced from each other. To make this somewhat clearer, it may be assumed that if a medial line be drawn from the toe of the form through the foot and down through 90 the leg to the base of the form, the bulge 95 constituting the thickest portion of the form will, in the foot portion and preferably in the lower leg portion, lie between the medial line and the rear edge of the form, and thereafter shift gradually inwardly away 100 from the rear edge.

105 It will be seen that by this construction of the form, a relatively larger quantity of heating medium used is provided in that portion of the form which dries the several reinforced sections of a stocking. Therefore, the reinforced portions will dry in substantially the same length of time as the lighter fabric of the stocking, thus providing uniform drying and eliminating to a great extent the "baking" of the lighter fabric while the reinforced sections are still to be thoroughly dried.

110 This construction of the form embodies, therefore, the practical advantages of a flat form and of an oval form, in that the wrinkles in the reinforced sections of a stocking are effectually removed, and at the same time the stocking will lie flat. The result is 115 materially to expedite production and, at the same time, produce a better and more uniform finish than is produced on forms heretofore constructed.

I claim:

120 1. A hosiery drying form having front and rear edges, said form in certain parts being of gradually increased thickness from the front to the region of the rear edge, and being of abruptly decreased thickness to the 125 rear edge.

2. A hosiery drying form hollow to contain a heating medium and provided with front and rear crease-producing edges, said form being of gradually increased transverse dimension from the front toward the rear crease-producing edge in certain parts of the form, said dimension being greatest along said rear edge, whereby to provide for uniform drying of the several portions of a 10 hosiery article placed on the form.

3. A hosiery drying form having front and rear edges and comprising a foot portion and a leg portion, the cross-sectional area in certain parts of such form including 15 the whole of the foot portion increasing gradually from one of said edges and increasing abruptly from the other edge in such manner that the form will be of greatest thickness at a point between the latter 20 edge and a medial line passed longitudinally through the form and adjacent said edge.

4. A garment drying form hollowed to contain a heating medium, said form having front and rear edges and sides of uniform thickness, the sides in certain parts of the form being farthest apart immediately adjacent one of the edges to provide a bulge in the hollow interior permitting a concentration of the heating medium in the 25 region of said edge, the form decreasing gradually in transverse dimension from the bulge to the other edge.

5. A garment drying form having curved sides, the curve of the sides varying intermediate the edges of the form in different longitudinal portions thereof, the region of greatest transverse thickness of the form lying along a longitudinal line intermediate the edges, said line at one end of the form 40 extending in closer proximity to one of said edges than to the other and shifting gradually inwardly away from said edge towards the other end of the form.

6. A hosiery drying form comprising a 45 foot portion and a leg portion having curved sides, the curve of the sides varying intermediate the edges of the form in different longitudinal portions thereof, the region of greatest transverse thickness of the form lying along a line intermediate the edges, said line in the foot portion and in the lower 50 leg portion extending in closer proximity to one of said edges than to the other and in the other parts of the form lying inwardly away from said edges.

7. A hosiery drying form hollow to contain a heating medium comprising opposing sides terminating in edges, the cross-sectional contour of the hollow interior conforming generally to the cross-sectional contour between said edges of the exterior drying surface, the sides immediately adjacent one edge of the form being farthest spaced 65 from each other to provide a concentration

of heating medium in the region of said edge.

8. A hosiery drying form hollow to contain a heating medium comprising opposing sides terminating in edges, the cross-sectional contour of the hollow interior conforming generally to the cross-sectional contour between said edges of the exterior drying surface, said form having its greatest internal and external transverse dimensions 70 immediately adjacent one edge to provide a concentration of heat radiating surface and heating medium adjacent said edge.

9. A hosiery drying form comprising opposing sides of light sheet material terminating in edges and which are spaced intermediate said edges to receive a heating medium, the cross-sectional contour of the hollow interior conforming generally to the cross-sectional contour between said edges of the exterior drying surface, said sides being bulged and farthest spaced from each other immediately adjacent one edge to provide a concentration of heating medium in the region of said edge, the sides tapering 75 from said bulged edge portion to the other edge of the form.

In testimony whereof, I affix my signature.
